UNITED STATES PATENT OFFICE

132,850

DESIGN FOR A PRESSING IRON STAND

William M. Cissell, St. Mathews, near
Louisville, Ky.

Application October 13, 1941, Serial No. 103,752

Term of patent 14 years

To all whom it may concern:

Be it known that I, William M. Cissell, a citizen of the United States, residing at St. Mathews, near Louisville, in the county of Jefferson and State of Kentucky, have invented a new, original, and ornamental Design for a Pressing Iron Stand, of which the following is a specification, reference being had to the accompanying drawings, forming part thereof.

Figure 1 is a perspective view of a pressing iron stand, showing my new design;

Figure 2 is a top plan view thereof;

Figure 3 is a longitudinal sectional view thereof on line 3—3 of Figure 1;

Figure 4 is a cross-sectional view thereof on line 4—4 of Figure 1; and

Figure 5 is a bottom plan view thereof.

I claim:

The ornamental design for a pressing iron stand, as shown.

WILLIAM M. CISSELL.
